UNITED STATES PATENT OFFICE

2,216,349

MACHINE FOR FORMING LINER BAGS FROM
THIN SHEET MATERIAL

Harry L. Jacoby, Philadelphia, Pa., and Isaac L. Wilcox, Fulton, N. Y., assignors to Oswego Falls Corporation, Fulton, N. Y., a corporation of New York

Application August 16, 1939, Serial No. 290,510

18 Claims. (Cl. 93—60)

This invention relates to a machine for forming bags from thin sheet material, and more particularly for forming bags from such material and inserting the same in a casing, the sheet material being moisture proof and the casing being formed of fibrous material, such as paper-board, whereby the bag serves as a liner to make a container suitable for liquid and moist products. A machine of this type is disclosed in the patent to 5 Wilcox, No. 2,152,941, April 4, 1939.

The present invention consists of certain improvements on the machine shown in the Wilcox patent, and has as an object a machine of the type referred to which is operable to automatically 10 form the liner bags from a web of sheet material, such as Cellophane, and to insert the formed bags in the container casings.

The invention has as a further object a machine of the type referred to embodying means 20 for automatically conveying the containers through the machine, automatically advancing the web of sheet material to the blanking mechanism, forming the bags and inserting the same in the containers, whereby the bags may be 25 formed and inserted in the containers at a comparatively rapid rate to obtain high production.

The invention has as a further object the provision of means for alining each container with the bag forming mechanism and securely holding 30 the container while the bag is being inserted and attached to the container.

The invention has as a further object a particularly novel mechanism for feeding the web of sheet material to the blanking mechanism of the 35 machine and maintaining the web in condition to effect the most efficient blanking of the same.

The invention has as a further object, mechanism for positively operating the folding fingers during the initial arrangement of the blank into 40 bag formation, and the invention further includes a particularly simple and convenient construction whereby the folding fingers are adjustable to accommodate blanks of different sizes, whereby liner bags for different size containers 45 may be produced by the machine without necessitating any appreciable change or modification of the machine.

The invention further consists in the novel features and in the combinations and constructions 50 hereinafter set forth and claimed.

In describing this invention, reference is had to the accompanying drawings in which like characters designate corresponding parts in all 55 the views.

Figure 1 is a top plan view of a machine illustrating our invention.

Figure 2 is a front elevational view of the machine.

Figure 3 is a side elevational view of the machine.

Figure 4 is a vertical sectional view of the ram, folding and pleating mechanism, and container support, with the frame of the machine and associated parts omitted.

Figure 5 is a fragmentary, vertical, sectional view of the folding and pleating mechanism.

Figure 6 is a fragmentary, top plan view of the folding mechanism.

Figure 7 is a horizontal, sectional view of the actuating mechanism for the folding and pleating mechanism and contiguous portions of the motion transmitting means for actuating the same.

Figure 8 is a side elevational view of the folding and pleating actuating means shown in Figure 7.

Figure 9 is a top plan view of one of the web gripping devices in a contiguous portion of the conveyor chain to which said devices are attached.

Figure 10 is an end elevational view of a gripper device with a contiguous portion of the blank cutter and guiding track shown in section and illustrating the web held taut across the cutter.

Figure 11 is an end elevational view of a gripper device and a contiguous portion of a sprocket wheel illustrating the gripper in web releasing position.

Figure 12 is a detail view of the container conveyor support and container support together with contiguous portions of the frame of the machine.

Figure 13 is a vertical sectional view, with parts in elevation, of the structure shown in Figure 12.

Figure 14 is a top plan view of the container support and contiguous portions of the container conveyor.

Figure 15 is a side elevational view of the structure shown in Figure 14.

The machine consists of a suitable frame including base members 10 and upwardly extending side members 11, 12. The base members 10 extend forwardly and rearwardly from the uprights 11, 12, and braces 13 extend rearwardly and downwardly from the upper portions of the members 11, 12, to the rear ends of the base members 10.

The folding and pleating mechanisms are carried by a support 14, the inner side of which is secured to the uprights 11, 12, and the outer or 50 55

front edge of the support 14 is carried by a pair of brackets 15, the upper ends of which are secured to a transversely extending cross member 17 welded, or otherwise secured, to the upper ends 5 of the side members 11, 12.

The stem 20, carrying the ram 21, is slidably mounted in bearings 22 formed in a supporting block 23 and secured to the cross member 17, as by bolts 24. The rear side of the stem 20 is 10 formed with gear teeth 25 with which a pinion 26 meshes. The pinion 26 is secured to the end of a shaft 27 rotatably journaled in a bearing 28 formed in the support block 23 between the bearings 22 and a bearing 29 formed in a bracket 15 30 secured to the cross member 17, see Figures 1, 3 and 4. The outer end of the shaft 27 is formed with gear teeth 31 forming a pinion with which a rack 32 meshes. The rack 32 is slidably mounted in the bracket 30, see Figures 3 and 4, 20 and upon reciprocation of the rack 32 the stem 20 and ram 21 are moved vertically to draw the blank through the folding and pleating mechanism. The mechanism for effecting reciprocation of the rack 32 will be hereinafter described.

25 The folding and pleating mechanism carried by the support 14 is similar in general arrangement to that shown in the patent to Wilcox previously referred to. The support 14 is formed with a central aperture arranged in alignment 30 with the ram 21, and a plurality of folding fingers 35 are pivotally mounted at their inner ends adjacent the aperture in the support and extend radially therefrom. These fingers normally lie in horizontal position and the outer 35 ends of the fingers move upwardly toward the ram as the same enters the aperture upon its downward stroke. The pivotal movement of the fingers is instrumental in arranging the blank of sheet material into bag formation.

40 As here shown, the fingers 35 are pivotally mounted on blocks 36 mounted in radially extending recesses 37 formed in the central portion 38 of the supporting plate 14. The central portion 38 is of reduced thickness. The blocks 36 45 are formed with an elongated slot 39 through which a clamping screw 40 extends and which is threaded into an aperture 41 of the support 14. The recesses 37 and slots 39 are of sufficient length to permit radial adjustment of the blocks 36, as indicated in Figures 5 and 6.

45 The inner ends of the blocks 36 are slotted as at 42, and the inner ends of the fingers 35 are pivotally mounted in these slots. As here shown, the fingers 35 are detachably secured to members 43 which are formed with an arcuate 50 portion having gear teeth 44 and a rearwardly extending tail piece 45. In the structure shown in Figure 5, the tail pieces 45 are secured to the members 43 by welding, as at 46. The top surface of the tail pieces 45 are formed with an axially extending rib, and the under side of the base portion of the fingers 35 is formed with a slot 47 to receive the rib on the tail piece, and the finger is detachably secured to the tail piece 60 by a screw 48. The members 43 are arranged in the slots 42 of the respective blocks 36 and are pivotally mounted upon pins 49. The rear portion of the tail piece 45 rests upon the upper face of the blocks 36 which are provided with circular 65 recesses 50 to receive the heads of the screws 48.

70 The inner portion of the blocks 36 is also formed with a vertically extending aperture 51 to slidably receive the racks 52, the teeth of which are arranged to mesh with the teeth 44 75 on the members 43. It will be apparent that,

upon vertical movement of the racks 52, the fingers 35 will be caused to pivot about the pins 49 and approach a vertical position. The positive and simultaneous vertical movement of all the racks 52 is effected by vertical movement of an 5 annular plate 55. The plate 55 is formed with slots 56 extending radially outwardly. The lower ends of the racks 52 are formed with a reduced portion 57 slidably mounted in the slots 56. It will be apparent that upon loosening the 10 clamping screws 40 the finger assembly, including blocks 36 and racks 52, may be adjusted radially, in which event the racks 52 move with the blocks 36, the reduced portions 57 of the racks sliding in the slots 56. Radial adjustment 15 of the finger assemblies requires the use of fingers of different lengths, as will be hereinafter apparent. However, this requirement is provided for in that the fingers 35 are readily detached from the members 43 by the screws 48. 20

The plate 55 is secured at its periphery to an annular member 60 as by a clamping ring 61 and screws 62. The annular member 60 is formed with a plurality of slots 63 extending at an angle to the axis of the member, see Figure 8. The 25 annular member is supported upon rollers 64 mounted upon studs 65 threaded into the periphery of a supporting ring 66 which, in turn, is secured to the under side of the support 14 by screws 67 which extend through spacing collars 30 68 interposed between the ring 66 and the under side of the support plate 14, see Figures 4 and 5. The plate 55 is provided with clearance apertures for the spacing collars 68 to permit vertical movement of the plate 55 relative to the support 35 14. In view of the angularity of the slots 63, rotation of the annular member 60 effects vertical movement thereof and accordingly, vertical movement of the plate 55 and racks 52.

The pleating mechanism includes an annular 40 series of depending fingers 70 secured at their upper ends to the inner ends of the blocks 36 as by screws or rivets 71. The fingers 70 are arranged in alignment with the fingers 35, see Figure 6.

45 A ring 72 of yieldable material, such as rubber, is arranged to encircle the fingers 70 adjacent their lower ends, and is mounted on a ring member 73 as by a clamping plate 74 and screws 75. The ring member 73 is mounted within an annular member 76 which, in turn, is mounted within the member 66, and the members 73, 76 are supported by a plate 78 secured to the lower edge of ring 66, as by screws 79. The periphery of the member 73 is formed with ratchet teeth 80, 55 and the member 76 is provided with one or more pawls 81. An arm 82 is secured to the member 76 and extends outwardly through a slot formed in the members 60, 66, see Figures 4 and 7. Motion transmitting mechanism is provided for oscillating both the members 60, 76, and oscillation of the member 76 effects intermittent rotation of the member 73 which carries the annular rubber member 72.

The machine also includes cutters operable 60 to shear or sever the blank from a web of sheet material. These cutters are in the nature of a stationary die 85 and a movable cutter 86. The die has a top cutting surface 87 and a radially extending flange 88 which is secured to the support 14 as by screws 89. It will be understood 70 that the die 85 is arranged concentrically of the pleating and folding mechanisms.

The cutter is preferably of the type disclosed in Patent No. 2,109,854 to Wilcox. The cutter is 75

carried by a pair of stems 90 slidably mounted in vertical bearings 91 formed on a bracket 92 which is secured to the uprights 11, 12, see Figures 2 and 3. The stems 90 are connected to the 5 ends of arms 93 by links 94. The arms 93 are integral with a rock shaft 95 journalled in bearings 96 mounted on the upper edge of the cross piece 17. One of the arms 93 extends rearwardly as at 97, and is pivotally connected to an adjustable link 98, the lower end of which is connected to an eccentric 99 mounted on a shaft 100. The shaft 100 extends transversely of the base members 10 and is journalled in bearings 101 and is rotated by a motor 102 through gears 103, 104. It will be apparent upon rotation of the shaft 100, the stems 90 will be reciprocated effecting movement of the cutter 86 toward and from the die 85 into and out of shearing relation with the same.

20 The sheet material is in the form of a roll 110 supported on a shaft 111 carried by brackets 112 secured to one of the base members 10 and extending upwardly therefrom. The web 113 of sheet material is passed over a tension roller 114, see Figure 2, and is fed between the cutting dies 85, 86 by mechanism operable to place the web under transverse tension as it passes between the cutters. This mechanism consists of a pair of endless chains 115 arranged in spaced apart 25 relationship and being trained over sprocket wheels 116. One pair of sprocket wheels 116 is mounted upon a shaft 117 journalled in bearings 118 supported by brackets 119. One of the brackets is secured to the upright 11, and the other bracket to the depending portion of the brace 15. The second set of sprockets 116 are mounted upon a shaft 120 journalled in bearings 121, one of which is secured to the forward side of the opposite brace 15, and the other bearing 30 is carried by a bracket secured to the upright 12. Preferably, a plurality of flat face pulleys 125 are arranged in spaced apart relationship on each of the shafts 117, 120. Each of the sprocket wheels 116 is formed with a radially extending flange 127 arranged in spaced apart relationship 35 to the teeth 128 of the sprocket and to the outside thereof. The wheels 116 are also formed with a cylindrical base 130 arranged to the inside of the teeth 128 and in spaced apart relation thereto.

40 Each of the chains 115 is provided at predetermined intervals with gripping members operable to grip the side edges of the web 113. These gripping members consist of inner and outer blocks 131 mounted upon pins 132 extending through the links of the chain 115. The inner block 131 is formed with an integral inwardly extending jaw 133, and is provided with an aperture to receive a stud 134 which is secured against rotation by a nut 135. A movable jaw 136 is 45 pivotally mounted upon the stud 134 with the jaw portion arranged directly over the jaw portion of jaw 133. The movable jaw 136 is formed with a depending portion 137 having an inwardly projecting pin 138 on which is journalled a roller 139. The movable jaw 136 is biased toward the rigid jaw 133 by a torsion spring 140 encircling stud 134, and the jaw 136 is moved upwardly or away from the jaw 133 as the gripping members successively engage the sprocket wheels 116, at 50 which time the roller 139 engages the cylindrical surface 130, see Figures 9, 10 and 11.

The general arrangement is such that the web 113 is received between the chains 115, with the central portion of the web supported by the 55 flat pulleys 125. The edges of the web pass over

the gripping portion of the stationary jaws 133. The movable jaws 136 at this time have been moved to open position by roller 139 engaging surface 130. As the gripping members pass out of engagement with the sprocket wheel 116 adjacent the roll of material 110, the edges of the web 113 are clamped against the lower jaw 133 by the movable jaw 136. As the gripping members and web progress toward the cutters 85, 86, each chain is biased outwardly to tension the 10 web. This is accomplished by a track 150 extending transversely of the support 14 on each side of the stationary cutter 85. The tracks diverge slightly toward the front and rear sides of the support 14 thus causing each of the chains 115 15 to move slightly outwardly from the stationary cutter 85, with the result that the web 113 is maintained in a taut condition across the cutting edge of the die, and a clear even blank is sheared from the web upon the descent of the cutter 86. 20

As the grippers and chain progress, the movable jaw 136 is released from the web upon engagement of the rollers 139 with the surface 130 on the opposite pair of sprocket wheels 116, and the waste portion of the web may be deposited in 25 a container or otherwise disposed of.

In order to prevent any twisting movement of the chain while the rollers 139 are in engagement with the surface 130, the outer block 131 is provided with a roller 155 which is arranged to 30 engage the flange 127 on the outer side of the sprocket wheel.

The shaft 120 is intermittently rotated in timed 35 relation to the movement of the cutter 86 to effect proper feeding of the web 113. A gear wheel 158 is rotatably mounted upon the shaft 120 between the inner sprocket wheel and bracket 119. A member 159 is secured to the gear 158 and is provided with a pair of spring actuated pawls 160 arranged in juxtaposition to the periphery of 40 a ratchet wheel 161 which is secured to the shaft 120. The wheel 158 is oscillated by a vertically extending rack 162 meshing therewith and being adjustably secured to the end of a connecting rod 163, as at 164. The opposite end of the connecting rod is secured to a disk 165 having a crank pin 166 adjustable to vary the stroke of the rod 163. The disk 165 is secured to a shaft 167 45 mounted in bearings 168 arranged on the base of the machine and being operatively connected to the drive shaft 100 through miter gears 169. 50

The rack 32 is connected to one arm 172 of an angle lever pivotally mounted upon a shaft 173 secured in brackets 174 mounted on the rear side of the vertical members 11, 12, the rack 32 being 55 connected to the arm 172 by a link 175. An adjustable link 176 is pivotally connected to the opposite arm 178 of the angle lever, and the lower end of this link is provided with an eccentric 179 operable by the shaft 100 to effect vertical reciprocation of the link 176 and accordingly, horizontal reciprocation of the rack 32.

The ring 76 is oscillated by a link 182 pivotally connected to the outer end of link 82 as by coupling 183. The opposite end of the link 182 is 60 pivotally connected to an arm 184 of a rocker member 185 pivoted on a shaft 186 mounted in brackets 187 secured to the members 11, 12. The rearwardly extending arm 188 of the rocker member is pivotally connected to a link 189 provided 65 at its lower end with an eccentric 190 operable by the shaft 100.

The annular member 60 is oscillated to effect pivotal movement of the fingers 35 by a link 191 pivotally connected at the forward end to a pro- 70 75

ection 192 extending from the periphery of the member 60. The link 191 is pivotally connected at its rear end to an arm 194 of a rocker member 195 which is also rotatably mounted upon the shaft 186. The rocker members 185, 195 are held from axial movement by collars 196. The rear-wardly extending arm 197 is pivotally connected to the upper end of a link 198, the lower end of which is provided with an eccentric 199 also operable by the shaft 100.

The containers or casings C, in which the liner bags are inserted, are conveyed beneath the bag forming mechanism carried by the support 14 by a conveyor extending from the front to the rear of the machine, the conveyor being operable to position the containers in axial alignment below the bag forming mechanism, and means is provided for effecting vertical movement of the container after the liner bag has been placed therein to fold the upper edge of the bag over the top edge of the container.

The container conveyor is supported by a pair of U shaped members 200. These members are formed with depending angle pieces 201 at their inner ends and with angular braces 202 extending from the lower ends of the depending pieces 201 upwardly and forwardly to the horizontal portion of the U members 200. The angle pieces 201 are slidable vertically on transversely extending angle plates 203 secured to the uprights 11, 12. The U members 200 are adjusted vertically by a screw 204 operated through gearing by a hand wheel 205.

The container conveyor consists of a forward and a rear section, the forward section being mounted upon and supported by the forward vertically extending leg portions of the U members 200, and the rear section of the conveyor being carried by the rear legs of said members. Each section of the conveyor is made up of a pair of spaced apart parallel extending side pieces here shown as consisting of upper and lower angle sections 206, 207. These sections are arranged with their sides in reverse order with a plate 208 secured between the angle pieces 206, 207. The angle pieces and the plates may be secured together in any suitable manner as by welding and the arrangement is such that the upper side of the angle piece 206 forms a guide rail for the containers, and the plates 208 form a support for the containers while they are being conveyed. The confronting edges of the plates 208 are spaced apart to permit operation of a conveyor chain 209 which is provided at intervals with container engaging members 210.

The angle pieces 206, 207 and plates 208 are arranged between the bag forming mechanism and the lower run of the chain 115. Plates 211 are secured to the forward and rear end of the forward and rear conveyor sections respectively and form supports in which shafts 212 are journaled and which carry the sprockets over which the endless conveyor chain 209 is trained. Preferably, one set of plates 211 are provided with means as screw 213 for adjusting the tension of the chain. The front and rear sections of the conveyor are arranged in alignment and the entire conveyor may be adjusted vertically toward and from the bag forming mechanism by operation of the hand wheel 205.

The forward and rear sections of the container conveyor are separated below the bag forming mechanism in order to accommodate a vertically movable container support. This support consists of a U shaped member having a base 215 and

vertically extending sides 216. The base 215 is supported by a shaft 217 slidably mounted in a bearing 218 secured to a cross piece 219 extending between the angle braces 202. The shaft 217 is connected to a shaft 220 slidably mounted in a cross piece 221 extending between the base members 10. The shafts 217, 220 are connected by an adjustable coupling 222 and the shafts, together with the container support, are movable vertically by a link 223 pivoted at 224 and actuated by a cam 225. A plate 226 is secured to each of the side members 216. The plates 226 extend inwardly to form a support 227 for the container, and extend outwardly an appreciable distance beyond the sides 216. The inwardly extending supporting surfaces 227 are arranged in alignment with the plates 208 and are of such length as to permit vertical movement between the confronting ends of the forward and rear section of the conveyor, whereby the container may be elevated toward the bag forming mechanism.

The movable container support is provided with means operable to arrange the container in axial alignment with the bag forming mechanism and to grip the container while the bag is being inserted into the container and the ram being withdrawn therefrom. This means consists of a pair of jaw members 230 arranged on each of the plates 226. The jaws 230 are pivotally connected at their ends to links 231 which are formed with angle arms 232. The arms 232 are pivotally connected at their ends by a link 233 and are yieldingly actuated to move the jaws 230 inwardly to grip a container by springs 234. A plate 235 is secured to each of the plates 226 in spaced apart relationship thereto and extend over the links 231. The plates are provided at their inner edges with vertically extending flanges 237 to form guide rails for the container. The plates 235 are secured to the plates 226 by screws 238 and spacers 239.

The jaws 230 are normally maintained in container gripping position by the springs 234. The links 231 and jaws 230 are actuated to move the jaws outwardly while the containers are being moved by the chain 209. This movement is effected by levers 240 pivoted at 241 to the rear legs of the U members 200. These levers are connected together by tie rods 242, and the levers are provided at their forward ends with upwardly extending cam projections 244. One of the levers 240 is provided with a rearwardly extending portion 245 which is engaged by a roller 246 secured to the link 176 which actuates the ram 21 vertically, as hereinbefore described. The links 233 are provided with laterally projecting pins 247 which are arranged to be engaged by the cam projections 244 on levers 240. The arrangement is such that during the downward stroke of the ram 21 through the bag forming mechanism and the insertion of the formed bag into the container on the container support, the forward ends of the levers 240 are moved downwardly out of engagement with the pins 247, whereby the container on the container support is gripped by the jaws 230.

After the bag has been inserted into the container, the container support is elevated by the cam 225 to move the top of the container into a heater ring 250 secured to the annular member 78 by screws 251. The heater ring 250 is maintained at the proper temperature by any suitable means as an electric heater coil 252. The lower portion of the ring 250 is tapered

as at 253. The formed bag is of such dimension that it projects slightly above the top edge of the container C. The top of the container is preferably coated with an adhesive reactivated by heat and accordingly, when the container support is elevated the upwardly extending top edge of the bag is folded over the top edge of the container by the conical bore 253 and ring 250, and the container is moved upwardly until the top edge of the container, with the bag folded thereunder, is positioned in the cylindrical bore 256 of the ring 250, whereupon the overfolded portion of the bag is secured to the top of the container or casing because of the heat transferred from ring 250.

The arrangement of the levers 240 and the roller 246 is such that the jaws 230 continue to grip the container during downward movement of the container support and while the ram is being withdrawn from the bag in the container, whereupon the roller 246 moves out of engagement with the rearwardly extending portion 245 of the lever 240, permitting the cam portions 244 of the levers 240 to move upwardly under the influence of spring 260 and into engagement with the pins 247 effecting outward movement of the jaws 230 to release the container. This movement takes place just previous to the movement of the conveyor chain 209. The shaft 212 supporting the rear sprocket wheel of the container conveyor is provided with a notched wheel 261 and a member 262 is loosely journaled upon the shaft and provided at one end with a pawl 263 operable to engage the teeth on the wheel 261. The opposite end of the member 262 is connected to an arm 264 by a link 265. The arm 264 is mounted upon a transversely extending shaft 266 journaled in bearings 267 arranged on the uprights 10, 11. The shaft 266 is oscillated by a link 268 reciprocated by an eccentric 269 secured to the shaft 100. This arrangement is such as to move the upper run of the conveyor chain 209 rearwardly to move a container off from the container support and to move another container thereon during which movement the jaws 230 are maintained out of container engaging position.

It will be understood that the arrangement of the eccentrics and cams on the shaft 100 and the intermittent drive for shaft 120 is such as to effect operation of the various moving parts of the machine in proper timed relationship.

Assuming the web is stretched taut across the stationary cutter 85, the operation of the machine is as follows: The movable cutter 86 descends and shears a circular blank from the web, the blank falling upon the horizontally extending fingers 35. During this movement the ram 21 descends and as it enters the aperture in the support 14, the member 60 is actuated causing the racks 52 to move the fingers 35 about their pivots toward vertical position. This movement of the fingers takes place while the ram is passing into the aperture. An annular member 270 is slidably mounted upon the ram or the stem 20 thereof. A plurality of bars or fingers 271 are secured to the annular member 270 and extend downwardly and inwardly toward the axis of the ram, see Figure 4. The fingers 271 are spaced apart circumferentially about the ram and are arranged intermediate the folding fingers 35 and are cooperable with those fingers to form the marginal portion of the blank into a plurality of radially extending folds. Downward

movement of the member 270 is controlled by a pair of rods 273 extending upwardly from the member 270 and being slidably arranged in a bifurcated bracket 274. The upper ends of the rods 273 are provided with adjustable heads 275. The member 270 is yieldingly urged downwardly to position the fingers 271 about the ram by helical compression springs 276.

It will be apparent as the ram passes into the aperture of the support 14 the blank is arranged into bag formation with the side wall of the bag being formed into a plurality of radially extending folds by the fingers 35, 251. These folds pass between the stationary fingers 10, and as the bag is drawn through the aperture the member 76 is rotated imparting a rotary motion to the rubber ring 72. The movement of the ring 72 arranges the radially extending folds into circumferentially extending pleats during the passage of the bag through the pleating and folding mechanism. The bag is now completely formed and further downward movement of the ram transfers the bag into a container C positioned upon the container support. During this downward movement of the ram, the levers 240 have been moved out of engagement with the pins 247, whereby the container is firmly gripped by the jaws 230.

Preferably, the blank is initially proportioned so that when it is formed into bag formation and the bag is pressed into the container, the open end of the bag projects upwardly beyond the top edge of the container. This upwardly extending portion of the bag is folded outwardly over the top edge of the container by a plurality of radially movable members 280 carried by the ram and which are actuated by a stem 281 provided with a piston 282 slidably mounted in a cylinder carried in the ram stem 20. A pipe 283 extends from the top of this cylinder upwardly through the ram and is connected to a source of air pressure by valve 284. When the ram reaches the end of its downward stroke, the valve 284 is open admitting air pressure against the top of piston 282, causing it and stem 281 to move downwardly and actuate the members 280 outwardly to fold the open end of the bag outwardly, as indicated at 285, Figure 2.

The ram thereupon moves upwardly and the container support is simultaneously elevated by cam 225 and lever 223. The ram continues to ascend until it reaches the top of its stroke. The top of the container is moved into engagement with the ring member 250 and the outwardly flaring portion of the bag is pressed against and sealed to the top of the container. The container support is then moved downwardly to normal position and the jaws 230 are moved out of engagement with the container. Thereupon the container conveyor chain 209 is indexed to move a new container onto the container support and after the ram has ascended sufficiently to clear the web 113 the chains 115 are advanced to feed a new portion of the web over the cutter die 85.

From the description of the structure, it will be apparent that we have devised a machine for forming liner bags and inserting the same in containers which operates entirely automatically. A roll of sheet material may be mounted upon the shaft 111 containing sufficient material to form liner bags for several thousand containers. The containers are deposited upon the front portion of the container conveyor and are automatically moved rearwardly in register with the bag forming mechanism, and after the bag has been 75

inserted in the container the finished containers are conveyed to the rear of the machine. Due to its automatic operation, this machine is capable of efficiently lining several hundred containers 5 per hour.

What we claim is:

1. A machine for forming bags from a web of thin sheet material comprising a frame, a support mounted on the frame, said support being 10 formed with a central aperture and being provided with folding mechanism, a pair of cutters arranged above said support, means operable to advance the web between said cutters, and web gripping members arranged on each side of the 15 web and operable to tension the web transversely, said cutters being operable to shear a blank from the web and deposit the same onto said folding mechanism, a ram slidably mounted in the frame and being movable into and out of said aperture, 20 and said folding mechanism being cooperable with said ram during movement of the same into said aperture to form the severed blank into a bag.

2. A machine for forming bags from a web of thin sheet material comprising a frame, a support carried by the frame, said support being 25 formed with a central aperture and being provided with folding mechanism, an annular cutter mounted on the support and being arranged 30 concentric with said aperture and folding mechanism, a second cutter normally spaced above said first cutter and being movable into and out of shearing relation with said first cutter, means operable to advance the web between said cutters, 35 gripping members arranged on each side of the web and operable to grip the edges thereof and to maintain the web under transverse tension, a ram slidably mounted in the frame and being movable through said cutters and into and out of 40 the aperture in said support, and said folding mechanism being cooperable with said ram upon movement of the same toward the support to form the severed blank into bag formation.

3. A machine for forming bags from a web of thin sheet material comprising a frame, a support mounted on the frame, said support being 45 formed with a central aperture and being provided with folding mechanism, a cutter mounted on the support and arranged concentric with said 50 aperture and said folding mechanism, a second cutter movable into and out of shearing relation with said first cutter, an endless series of gripping members movable along opposite sides of said cutters and operable to grip the side edges 55 of the web and feed the same between said cutters, said cutters being cooperable during said shearing relation to sever a blank from said web and deposit the blank on said folding mechanism, a ram slidably mounted in the frame and being 60 movable through said cutters and into and out of said aperture to draw the blank therethrough, said folding mechanism being cooperable with said ram to form a blank into bag formation.

4. A machine for forming bags from a web of thin sheet material comprising a frame, a support carried by the frame, said support being 65 provided with a central aperture, folding mechanism carried by the support, an annular cutter mounted on the support concentric with said aperture 70 and said folding mechanism, a second cutter movable into and out of shearing relation with said first cutter, an endless chain operable along each side of said cutters, said chain being provided with a plurality of gripping members and means 75 operable to cause said gripping members to grip

the side edges of the web and advance the same between said cutters, and means operable to effect a spreading movement of said chains to maintain the web under transverse tension, a ram 5 slidably mounted in the frame and being movable through said cutters into and out of the aperture in said support to draw the blank therethrough, and said folding mechanism being cooperable with said ram to form the blank into bag formation.

5. A machine for forming bags from thin sheet material comprising a frame, a support mounted on the frame and being formed with a central aperture, a plurality of folding fingers pivotally 10 mounted on said support and extending radially 15 from said aperture, a ram slidably mounted in the frame and movable into and out of said aperture, said fingers being normally arranged in horizontal position to receive a blank of sheet material and being movable toward vertical position and being cooperable with the ram during 20 such movement to form the blank into bag formation, and motion transmitting means cooperable with said ram and said fingers to effect pivotal movement of said fingers upon movement 25 of the ram toward said aperture.

6. A machine for forming bags from thin sheet material comprising a support formed with a central aperture, a plurality of fingers pivotally 30 mounted on said support and extending radially 35 from said aperture, said fingers being normally arranged in horizontal position to receive a blank of sheet material, a ram slidably mounted in the frame and movable into and out of said aperture to draw the blank therethrough, and motion 40 transmitting means carried by said support and operable upon movement of said ram toward the support to effect pivotal movement of said fingers toward vertical position.

7. A machine for forming liner bags from thin 45 sheet material comprising a frame, a support carried by the frame and provided with a central aperture, a plurality of folding fingers pivotally 50 mounted adjacent said aperture and extending radially therefrom, each of said fingers being provided with a pinion, a rack slidably mounted in said support and arranged to engage each of said pinions, said rack and pinions being cooperable upon vertical movement of said 55 rack to effect movement of said fingers from horizontal to vertical position, a ram slidably mounted in the frame and movable into and out of said aperture, said fingers being normally arranged in horizontal position to receive a blank of sheet material, and motion transmitting means cooperable with said racks and said ram to effect vertical movement of said rack upon movement of said ram toward said support.

8. A machine for forming liner bags from thin sheet material comprising a frame, a support 60 carried by the frame and provided with a central aperture, a plurality of folding fingers pivotally 65 mounted on said support adjacent said aperture and extending radially therefrom, a ram slidably mounted in the frame and movable into and out of said aperture, said fingers normally 70 extending in a horizontal position, motion transmitting means cooperable with said fingers and said ram to effect movement of said fingers to vertical position during movement of the ram toward said support, and means for adjusting said fingers and said motion transmitting means radially toward and from the axis of said aperture.

9. A machine for forming liner bags from thin sheet material comprising a frame, a support car- 75

- ried by the frame and provided with a central aperture, a plurality of folding fingers pivotally mounted on said support adjacent said aperture and extending radially therefrom, a pinion secured to each of said fingers, a rack cooperable with each of said pinions, and said racks being mounted in said support and being slideable axially thereof, said racks and pinions being cooperable upon vertical movement of said racks to effect movement of said fingers from horizontal to vertical position, a ram slidably mounted in the frame and movable into and out of said aperture, motion transmitting means cooperable with said racks and said ram to effect vertical movement of said racks upon movement of said ram toward said support, and means for adjusting said fingers and said racks radially toward and from the axis of said aperture.
10. A machine for forming liner bags from thin sheet material comprising a frame, a support carried by the frame and provided with a central aperture, a ram slidably mounted in the frame and movable into and out of said aperture, a plurality of blocks mounted on said support and being adjustable toward and from the axis of said aperture, a holding finger pivotally mounted on each of said blocks, said fingers normally extending in horizontal position to receive said sheet material, and motion transmitting means cooperable with said fingers and said ram to effect movement of said fingers toward vertical position upon movement of said ram toward said aperture.
11. A machine for forming liner bags from thin sheet material comprising a frame, a support carried by the frame and provided with a central aperture, a ram slidably mounted in the frame and movable into and out of said aperture, a plurality of blocks mounted on said support and being adjustable radially toward and from said aperture, each of said fingers being provided with a pinion portion, an annular member arranged below said support, a plurality of racks carried by said annular member, each of said racks engaging the pinion portion of one of said fingers and being cooperable therewith upon upward movement of said annular member to move said fingers from horizontal to vertical position, and motion transmitting means cooperable with said ram and said annular member to effect upward movement of the latter upon movement of the ram toward said aperture.
12. A machine for forming liner bags of thin sheet material comprising a frame, a support carried by the frame and provided with a central aperture, a ram slidably mounted in the frame and movable into and out of said aperture, a plurality of blocks mounted on said support and being adjustable radially toward and from said aperture, a folding finger pivotally mounted on each of said blocks, and each of said fingers being provided with a pinion portion, an annular member arranged below said support and being movable vertically toward and from said support, said annular member being formed with a plurality of slots extending radially from said aperture, a rack mounted in each of said slots and being cooperable with the pinion portion of each of said fingers to effect vertical movement thereof upon upward movement of said annular member, each of said racks being adjustable radially in said slots, and motion transmitting means cooperable with said ram and said annular member to effect upward movement thereof upon movement of the ram toward said aperture.
13. A machine for forming liner bags from thin sheet material comprising a frame, a support carried by the frame and being provided with a central aperture, a ram slidably mounted in the frame and being movable into and out of said aperture, a plurality of blocks mounted on said support and being adjustable radially toward and from said aperture, a folding finger pivotally mounted on each of said blocks and extending radially from said aperture, each of said folding fingers being provided with an inward portion, a pleating finger fixedly secured to each of said blocks and depending axially in said aperture, an annular member arranged below said support and being movable vertically toward and from the same, a plurality of racks secured to said annular member, each of said racks being cooperable with the pinion portion of each of said folding fingers to effect movement of the same toward vertical position upon upward movement of said annular member, each of said racks being radially adjustable on said annular member toward and from the axis of said aperture, and motion transmitting means cooperable with said ram and said annular member to effect vertical movement of the latter upon movement of the ram toward said aperture.
14. A machine for forming liner bags of thin sheet material and inserting the same in containers comprising a frame, a support carried by the frame and being provided with a central aperture, a ram slidably mounted in the frame and movable into and out of said aperture, a plurality of folding fingers pivotally mounted on said support and extending radially from said aperture, said fingers being cooperable upon movement of the ram towards said aperture to form a sheet of said material into bag formation, and said ram being operable to press said bag through said aperture and into a container positioned below said support, a container conveyor arranged below said support, said conveyor comprising a forward section and a rear section, a container support arranged intermediate said sections and normally positioned in register therewith to receive a container conveyed by said conveyor, means carried by said container support and operable to position a container in register with said aperture.
15. A machine for forming liner bags of thin sheet material and inserting the same in containers comprising a frame, a support carried by the frame and being provided with a central aperture, a ram slidably mounted in the frame and movable into and out of said aperture, a plurality of folding fingers pivotally mounted on said support and extending radially from said aperture, said fingers being cooperable upon movement of the ram towards said aperture to form a sheet of said material into bag formation, and said ram being operable to press said bag through said aperture and into a container positioned below said support, a container conveyor arranged below said support, said conveyor comprising a forward section and a rear section, a container support arranged intermediate said sections and normally positioned in register therewith to receive a container conveyed by said conveyor, means carried by said container support and operable to position a container in register with said aperture, and means operable to move said container conveyor upwardly to move the upper edge of the container in engagement with said support.
16. A machine for forming liner bags of thin sheet material and inserting the same in con-

5 tainers comprising a frame, a support carried by the frame and being provided with a central aperture, a ram slidably mounted in the frame and movable into and out of said aperture, a plurality of folding fingers pivotally mounted on said support and extending radially from said aperture, said fingers being cooperable upon movement of the ram towards said aperture to form 10 a sheet of said material into bag formation and said ram being operable to press said bag through said aperture and into a container positioned below said support, a container conveyor arranged below said support, said conveyor comprising a forward section and a rear section, 15 means operable to adjust said conveyor sections in unison toward and from said support, a container support arranged intermediate said sections and normally positioned in register therewith to receive a container conveyed by said conveyor, means carried by said container support and operable to position a container in register with said aperture.

17. A machine for forming liner bags from a web of thin sheet material and inserting the bags 20 in containers comprising a frame, a support carried by the frame, said support being formed with a central aperture extending therethrough, folding mechanism carried by said support, a ram slidably mounted in the frame and movable into 25 and out of said aperture and being cooperable with said folding mechanism to form a blank into bag formation, a container support arranged below said first mentioned support coaxially with the aperture therein, means operable to move 30 said ram downwardly through said aperture and folding mechanism to position the formed bag 35

5 into a container on said container support, and container engaging members carried by the container support and operable to grip the container during movement of the ram into and out of the container and to subsequently release the container.

18. A machine for forming bags from a web of thin sheet material comprising a frame, a support carried by the frame and being formed in an aperture extending therethrough, a die arranged above said support concentrically with the aperture thereof, a cutter slidably mounted in the frame, an endless series of gripping members movable along opposite sides of the die and operable to grip the side edges of a web of sheet 15 material and feed the same between the die and cutter, means operable during movement of said gripping members in proximity to the die to move each series of members outwardly from the axis of the die to maintain the web taut, said 20 cutter being movable into and out of shearing relation with said die and operable to shear a blank from said web, a plurality of fingers pivotally mounted on said support and arranged to receive the blank, a ram slidably mounted in the 25 frame and being movable into and out of said aperture to draw the blank therethrough, means operable to effect pivotal movement of said fingers upon movement of the ram into said aperture, means cooperable with said fingers during 30 such pivotal movement to arrange the blank in bag formation, and means operable to move said cutter into shearing relation to the die and subsequently move the ram through said aperture.
